BELL RINGING DEVICE FOR LOCOMOTIVES

Louis E. Faulkner, Hattiesburg, Miss.

Application June 9, 1934, Serial No. 729,860

8 Claims. (Cl. 121—2)

This invention relates to a bell ringing device for locomotives, the general object of the invention being to provide automatic means for ringing the bell when the locomotive is in motion, the ringing ceasing when the locomotive is not in motion, whereby the ringing of the bell is not left to the action of the engineer.

This invention also consists in certain other features of construction and in the combination 10 and arrangement of the several parts, to be hereinafter fully described, illustrated in the accompanying drawings and specifically pointed out in the appended claims.

In describing the invention in detail, reference 15 will be had to the accompanying drawings wherein like characters denote like or corresponding parts throughout the several views, and in which:—

Figure 1 is an elevation of the front part of a 20 locomotive, showing the invention applied thereto.

Figure 2 is a vertical sectional view through the invention.

In these drawings, the device is shown at A 25 and is located on any suitable part of the front part of the locomotive and consists of a hollow base 1 forming an air chamber 2 which has an opening in one end thereof closed by a plug 3. A pipe 4 is in communication with the other end of the chamber and leads to the pneumatic bell 30 ringer B of the bell C. The bell ringer is of the usual or any desired type. A cylinder 6 has a reduced part 7 provided with a flange 8 which is bolted to the top of the base 1, as shown at 9. A sheet 10 of asbestos packing is located between the parts to retard transfer of heat from the base 35 to the lower part of the cylinder. The cylinder has a head 11 bolted thereto and a piston 12 is located in the cylinder and has a stem 13 depending into the reduced part 7. A valve chamber 14 is formed in a part of the wall of the cylinder 6 and is in communication with the cylinder through the port 15, the chamber having a reduced lower part 16, the junction of which with the large part forms a valve seat for a ball valve 40 17. A pipe 18 connects the large part of the valve chamber 14 with either end of either cylinder 19 of the locomotive and a pipe 20 connects the lower end of the small part 16 with the steam supply pipe 21 of the locomotive and a pipe 22 connects the cylinder, at the point of junction of the lower part thereof with the reduced part 7, with the exhaust passage of a locomotive cylinder, or this drain pipe 22 may exhaust at any other convenient point.

55 An air cylinder 23 is bolted to the top of the

base 1, as shown at 24, and has a sheet 25 of asbestos or the like insulating it from the base and this cylinder has a head 26 bolted thereto and a passage 27 connects the lower part of the cylinder with the chamber 2. A pipe 28 connects the upper part of the cylinder 23 with the air reservoir 5 of the locomotive. A sleeve 29 is located in the lower part of the cylinder 23 and the upper end thereof forms a valve seat for a ball valve 30 which separates the upper end of the passage 27 from the pipe 28, the sleeve having a port 31 therein which registers with the upper end of the passage 27. A cup member 32, formed of asbestos or the like, seats on a steel tip 33 and a bolt 34 passes through a sleeve 35, through a hole in the cup member into the tip and these parts form a stem for the valve 30. An opening 36 is formed in the lower part of the cylinder 6 and an opening 37 is formed in the lower part of the cylinder 23 for the passage of a lever 38 which has a notch 39 adjacent one end thereof which fits over a fulcrum projection 40 on a plate 41 fastened to the top of the base by a screw 42.

Thus it will be seen that when the locomotive throttle is opened, steam will pass through the steam pipe 21 into the cylinders 19 of the locomotive and some of this steam will pass through the pipe 20 into the lower part of the valve chamber 14 of the cylinder 6. Of course, the steam going to the locomotive cylinders will cause the locomotive to move in the usual manner and the steam passing through the pipe 20 will lift the valve 17 so that the steam will pass through the chamber 14 and through port 15 into the cylinder 6 and the pressure of this steam in the cylinder 6 will cause the piston 12 to move downwardly so that its stem will rock the lever 38 so as to raise the short end thereof so that the valve stem in the cylinder 23 is raised, which unseats the valve 30. When this occurs, air from the reservoir 5 of the locomotive passes through the pipe 28 into the cylinder 23, by the valve 30 and through the port 31 and passage 27 into the air chamber 2. The air passes from this chamber 2 through the pipe 4 to the pneumatic bell ringer B, which causes the bell C to ring in the usual manner.

As long as the locomotive throttle is open and/or there is steam pressure in the main steam pipe of the locomotive, all of the mechanical parts of the control device are at rest in the position described and illustrated in Figure 2, and air passes to the pneumatic bell ringer. When the throttle of the locomotive is closed, the valve 17 seats itself by gravity. Steam or

compression in the locomotive cylinder on the forward stroke of the piston enters and passes through the valve chamber 14 and through the port 15 to the cylinder 6, and action as described above takes place. On the backward stroke of the locomotive piston and/or when no pressure is exerted on the piston 12, air from the main reservoir, acting on the valve 30, seats the same, shutting off the supply of air to the reservoir 2. The reservoir 2 is so proportioned as to furnish enough head of air pressure for the operation of the pneumatic bell ringer during the alternate opening and closing of the ball check 30, during such time as the locomotive may be drifting and not working steam.

When no further pressure is exerted on the piston 12, either by live steam from the throttle or by compression in the locomotive cylinder having been reduced to zero through the locomotive and consequently piston stopping, then the air pressure, acting on the valve 30, seats the same and cuts off the air supply to the reservoir 2. Thus, after the pressure remaining in the reservoir 2 is exhausted, the bell ringer ceases action until the locomotive is moved again.

A housing D encloses the parts and is connected with the base 1 by the screws 1'.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:—

1. In a locomotive including a pneumatic device for ringing the bell thereof, means for connecting the said device with the air reservoir of the locomotive, and automatic means operated by the steam supplied to the locomotive cylinders for controlling the supply of air to said pneumatic device, such automatic means permitting the flow of air to the device while the locomotive is in motion, but cutting off the supply as soon as the locomotive ceases to move.

2. In a locomotive including a pneumatic bell ringer, an air chamber, a conduit connecting the same to the bell ringer, a conduit connecting the air chamber to the air reservoir of the locomotive, a valve in the conduit normally held closed by the air pressure in the reservoir, and means connected with a cylinder of the locomotive and operated by the pressure therein for moving the valve to open position.

3. In a locomotive including a pneumatic bell ringer, an air chamber, a conduit connecting the same with the bell ringer, a conduit connecting the chamber with the air reservoir of the locomotive, a valve in the conduit normally held closed by the air pressure in the reservoir, and means connected with a cylinder of the locomotive and with the main steam pipe leading to the cylinder and operated by pressure in said cylinder and said steam pipe for opening the valve.

4. In a locomotive including a pneumatic bell ringer, an air chamber, a conduit connecting the same with the bell ringer, a conduit connecting the chamber with the air reservoir of the locomotive, a valve in the conduit normally held closed by the air pressure in the reservoir, means connected with a cylinder of the locomotive and with the main steam pipe leading to the cylinder and operated by pressure in said cylinder and said steam pipe for opening the valve,

such means including a cylinder, pipes connecting the same with the locomotive cylinder and with the said steam pipe, a piston in the cylinder acted on by the steam entering the cylinder, and means operated by said piston for raising the valve.

5. In a locomotive including a pneumatic bell ringer, an air chamber, a conduit connecting the same with the bell ringer, a conduit connecting the chamber with the air reservoir of the locomotive, a valve in the conduit normally held closed by the air pressure in the reservoir, means connected with a cylinder of the locomotive and with the main steam pipe leading to the cylinder and operated by pressure in said cylinder and said steam pipe for opening the valve, such means including a cylinder, pipes connecting the same with the locomotive cylinder and with the said steam pipe, a piston in the cylinder acted on by the steam entering the cylinder, means operated by said piston for raising the valve, such means including a lever having one end engaged by a part of the piston, and means engaged by the other end of the lever for raising the valve off its seat.

6. In a locomotive including a pneumatic bell ringer, an air chamber, a conduit connecting the same with the bell ringer, a conduit connecting the chamber with the air reservoir of the locomotive, a valve in the conduit normally held closed by the air pressure in the reservoir, means connected with a cylinder of the locomotive and with the main steam pipe leading to the cylinder and operated by pressure in said cylinder and said steam pipe for opening the valve, such means including a cylinder, pipes connecting the same with the locomotive cylinder and with the said steam pipe, a piston in the cylinder acted on by the steam entering the cylinder, means operated by said piston for raising the valve, such means including a lever having one end engaged by a part of the piston, means engaged by the other end of the lever for raising the valve off its seat, said cylinder having a chamber therein, a valve separating the upper and lower parts of the chamber, the pipe leading from the steam pipe entering the lower part of said chamber below the valve and the pipe leading from the locomotive cylinder entering the chamber above the valve, the upper part of the chamber being in communication with the cylinder.

7. In a locomotive including a pneumatic bell ringer, an air chamber, a conduit connecting the same with the bell ringer, a conduit connecting the chamber with the air reservoir of the locomotive, a valve in the conduit normally held closed by the air pressure in the reservoir, means connected with a cylinder of the locomotive and with the main steam pipe leading to the cylinder and operated by pressure in said cylinder and said steam pipe for opening the valve, such means including a cylinder, pipes connecting the same with the locomotive cylinder and with the said steam pipe, a piston in the cylinder acted on by the steam entering the cylinder, means operated by said piston for raising the valve, and a drain pipe leading from the cylinder below the piston.

8. In a locomotive including a pneumatic bell ringer, a base supported on the locomotive and having an air chamber therein, a pipe connecting the chamber with the bell ringer, a cylinder supported on the base, a pipe connecting the upper part of the cylinder with the air reservoir of the locomotive, said cylinder having a pas-

sage connecting its lower part with the air chamber, a valve located between the upper part of the cylinder and the passage and normally held closed by the air pressure in the air reservoir, 5 a second cylinder supported on the base and having a valve chamber in one wall, the upper part of which is in communication with the cylinder, a pipe connecting the upper part of said chamber with an end of one of the locomotive cylinders, a pipe connecting the lower part of the last mentioned chamber with the main steam supply pipe of the locomotive, a valve in
 10 said chamber separating the upper part from the lower part, a piston in the cylinder, a lever supported from the base, a stem on the piston engaging one end of the lever, a stem in the first mentioned cylinder engaging the other end of the lever and acting to unseat the valve in the first mentioned cylinder when the lever is moved by downward movement of the piston, and a drain pipe connected with the second cylinder below the piston thereof. 80
